US00D769274S

(12) **United States Design Patent** (10) **Patent No.:** **US D769,274 S**
Rhodes et al. (45) **Date of Patent:** **** Oct. 18, 2016**

(54) **DISPLAY SCREEN WITH A GRAPHICAL USER INTERFACE**

(71) Applicant: **Square, Inc.**, San Francisco, CA (US)

(72) Inventors: **Matthew Rhodes**, San Francisco, CA (US); **Brian Grassadonia**, San Francisco, CA (US); **Jack Dorsey**, San Francisco, CA (US)

(73) Assignee: **Square, Inc.**, San Francisco, CA (US)

(**) Term: **14 Years**

(21) Appl. No.: **29/488,588**

(22) Filed: **Apr. 21, 2014**

(51) **LOC (10) Cl.** **14-04**

(52) **U.S. Cl.**

USPC **D14/486**; D14/490

CLAIM

The ornamental design for a display screen with a graphical user interface, substantially as shown and described.

DESCRIPTION

The FIGURE is a front view of a display screen with a graphical user interface showing our new design.

The broken line showing of the display screen and all other broken lines showing portions of the graphical user interface are included for the purpose of illustrating portions of the article and form no part of the claimed design.
